UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,264,217.

Specification of Letters Patent. Patented Apr. 30, 1918.

Original application filed May 4, 1917, Serial No. 166,377. Divided and this application filed July 23, 1917. Serial No. 182,308.

To all whom it may concern:

Be it known that I, WILLIAM A. SMITH, a citizen of the United States, residing at Denver, in the county of Denver and State of Colorado, have invented certain new and useful Improvements in Rock-Drills, of which the following is a specification.

The present invention in its preferred embodiment relates to rock drills of the hammer type, and one of the primary objects is to provide a novel and simple combination of great effectiveness, including a hammer piston that can be reversed, so that either end may be utilized for delivering the blow, and at the same time so construct said piston and parts associated therewith, that cleansing fluid can be delivered to the drill bit, irrespective of the reversal of the piston.

20 The present application is a division of my co-pending application, Serial No. 166,377, filed May 4, 1917.

The drawing is a longitudinal sectional view through the preferred embodiment of 25 the invention.

In the embodiment illustrated, the drill actuating motor comprises a cylinder member, which consists of a body 7, a rear head 8, and a front head 9. The body 7 is provided with a piston head chamber 11 and the rear head 8 has a neck chamber 12 communicating with the rear end of the chamber 11, and having an enlarged rear portion 13. The front end of the body 7 is provided with 35 a reduced portion 14, in which is formed a forwardly extending neck chamber 15 that communicates with the front end of the chamber 11, said neck chamber 15 having an open front end.

40 Operating in the cylinder member is a piston, comprising a central head 16 that reciprocates in the head chamber 11, said head being provided with integral oppositely extending necks 17 and 18, these necks 45 being duplicates one of the other, and operating respectively in the neck chambers 12 and 15. The neck 17 is provided contiguous to the head 16 with a reduced portion forming an annular channel 19, while the neck 18 50 has a corresponding portion or channel 20. The enlarged rear end of the neck 17, it will be noted, is movable into the enlarged portion 13 of the neck chamber 12, while the front end of the front neck 18 is adapted to

pass beyond the reduced portion 14, in which the neck chamber 15 is located.

A tapered valve seat 23, is provided in which is rotatably mounted a tapered valve 24. The motive fluid is controlled by said valve. This valve is provided with a longitudinal channel 26 communicating with the chamber 22, and said channel has a lateral port 27 that is movable into and out of communication with a passageway 28 formed longitudinally in the rear head 8 and the body 7. The passageway has a lateral port 29 communicating with the enlarged portion 13 of the neck chamber 12. Another lateral port 30 opens into an annular groove 31 formed in the front portion of the neck chamber 12. A third port opens into an annular groove 33 formed in the rear portion of the front neck chamber 15.

It will be evident that when motive fluid is admitted to the passageway 28, by turning the throttle valve 24, so that the port 27 will register with said passageway, motive fluid will be constantly in the rear enlarged portion 13 of the neck chamber 12, and also will enter the grooves 31 and 33 with the hammer piston in the position illustrated. This motive fluid will find its way from the groove 33 into the head chamber 11 in advance of the piston head 16 because of the position of the channel 20, whereas the fluid from the groove 31 will be cut off from admission to the rear of the head 16. The portion of the head chamber 11 in rear of said head is, however, open to the atmosphere through an exhaust port 34. As a consequence, the motive fluid acting against the front face of the head 16 will drive the piston rearwardly until the front portion of the groove or channel 20 is cut off from the groove 33. The rearward movement of the piston will of course carry the groove or channel 19 of the rear neck 17 to a position where it will afford communication between the groove 31 and the rear end of the head chamber 16, whereupon motive fluid will operate against the rear face of the piston head 16 and drive the piston forwardly. When in this position, the exhaust port 34 is in communication with the front portion of the head chamber 11 in advance of the head 16.

The front head 9 is extended to form an internal chamber 35 in which is rotatably

mounted a chuck 36 having an angular socket 37 adapted to receive the drill steel or bit 38 operated on by the hammer piston.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In drilling apparatus, the combination with a cylinder member having a head chamber and oppositely disposed neck chambers extending from the head chamber, of a reversible piston comprising a head operating in the head chamber and oppositely extending necks operating respectively in the neck chambers, means controlled by the necks respectively for alternately supplying motive fluid to opposite sides of the head, said means being controlled by either neck in either neck chamber, means for maintaining a constant supply of fluid under pressure against a rear surface of the neck in the rear neck chamber, the other neck constituting a hammer head for delivering the blows of the piston, and means for holding a tool in line with said other neck to receive the force of such blows.

2. In drilling apparatus, the combination with a cylinder member having a head chamber and oppositely disposed neck chambers extending from the head chamber, of a reversible piston comprising a head operating in the head chamber and oppositely extending necks operating respectively in the neck chambers, a motive fluid supply means having admission ports for respectively supplying motive fluid to the head chamber on opposite sides of the piston head, said necks having means for alternately admitting and cutting off the supply from the ports to the head and either neck operating to thus control the ports in either neck chamber accordingly as the piston is reversed, said motive fluid supply means also having a port ad-

mitting a constant supply of motive fluid into the rear neck chamber to constantly act against the rear surface of the neck therein, the other neck constituting a hammer head for delivering the blows of the piston, and means for holding a tool in line with said other neck to receive the force of such blows.

3. In drilling apparatus, the combination with a cylinder member having a head chamber and oppositely disposed neck chambers extending from the head chamber, of a reversible piston comprising a head operating in the head chamber and oppositely extending necks operating respectively in the neck chambers, motive fluid supply means including a controlling valve and a conduit disposed longitudinally of the cylinder member, said conduit having a lateral port communicating with the rear neck chamber to constantly admit motive fluid thereto against the rear end of the neck therein, and other lateral ports for respectively supplying motive fluid to the head chamber on opposite sides of the piston head, said necks having means for alternately admitting and cutting off the supply from the ports to the head and either neck operating to thus control the ports in either neck chamber accordingly as the piston is reversed, the forward neck in either case constituting a hammer head for delivering the blows of the piston, and means for holding a tool in line with the front neck chamber to receive such blows from the piston.

4. In apparatus of the character described, the combination with a cylinder member having neck chambers associated therewith, of a piston head operable in the cylinder member and having necks carried thereby for interchangeably engaging the neck chambers, a constant air chamber communicating with one of the neck chambers, and a chuck located in advance of the other neck chamber for receiving a tool to be operated on by the piston.

In testimony whereof, I affix my signature in the presence of two witnesses.

WILLIAM A. SMITH.
